UNDERREAMER

Reuben C. Baker, Coalinga, Calif., assignor to
 Baker Oil Tools, Inc., Vernon, Calif., a corpora-
 tion of California

Application June 17, 1942, Serial No. 447,892

4 Claims. (Cl. 255—76)

1

This invention relates to earth boring tools, and particularly to rotary drilling tools capable of enlarging the diameter of a well bore below a well casing.

It is an object of the present invention to provide an improved underreamer especially adapted for operation in hard formations having roller cutters that can be held positively in expanded position in such manner as to prevent the reactive force of the formation on the cutters from moving them inwardly to a position of smaller effective diameter.

A further object of the invention is to provide an improved underreamer having roller cutters positively held in expanded position, whose extent of outward expansion is positively limited.

Yet another object of the invention is to provide an improved underreamer employing roller cutters held in expanded position by the drilling weight imposed upon the tool.

Another object of the invention is concerned with the automatic retraction of the roller cutters of an underreamer by the simple expedient of raising or elevating the drilling string to which the underreamer is attached.

Yet another object of the invention resides in the provision of an improved hydraulically expandable roller underreamer of sturdy and simplified construction, capable of efficiently operating upon a shoulder formed in comparatively hard formations, for the purpose of materially enlarging the well bore below a casing shoe.

This invention has other objects that will become apparent from a consideration of the embodiment shown in the drawings accompanying and forming part of the present specification. This form will now be described in detail to illustrate the general principles of the invention, but it is to be understood that such detailed description is not to be taken in a limited sense, since the scope of the invention is best defined by the claims appended hereto.

Referring to the drawings:

Figure 1 is a longitudinal section through an hydraulically expandable roller underreamer, with certain parts in retracted position to enable free passage of the tool through a well casing;

Figure 2 is a view on an enlarged scale of part of the device, taken generally along the line 2—2 in Figure 1;

Figure 3 is a view similar to Figure 1, disclosing the underreamer cutters and associated parts in expanded position;

Figure 4 is a cross-section taken along the line 4—4 in Figure 1;

2

Figure 5 is a cross-section taken along the line 5—5 in Figure 3; and

Figure 6 is a bottom plan view of the pilot portion of the underreamer taken along the line 6—6 in Figure 3.

In its general aspects, the invention is concerned with an underreamer that can be lowered through a well casing with its roller cutters in retracted position, to enable the tool to pass readily through the casing to any required position in an open well bore below the casing shoe. When this position is reached, the supporting members for the roller cutters are elevated hydraulically and caused to ride up inclined or cam expander portions on the main body of the underreamer to force the roller cutters radially outwardly for enlarging the well bore in excess of the inside diameter of the casing through which the tool has passed. In a preferred form, the rollers are such as to first form a shoulder in the formation and then operate upon this shoulder to effect the desired increase in the diameter of the bore hole.

The supporting members and associated roller cutters expand outwardly upon their upward movement to a position in which the reactive force of the wall of the formation on the roller cutters and supporting members is transmitted directly to the main body of the underreamer in such manner as to positively prevent the outwardly expanded members from moving inwardly. As a result, the roller cutters remain in fully expanded condition for the purpose of enlarging the bore hole to the specified diameter. When in this expanded position, the drilling weight on the tool is imposed directly on the roller cutters through their supporting members, thereby relieving many of the underreamer parts from the drilling load. The extent of outward expansion of the roller cutters is also preferably limited by engagement of the supporting members with a suitable abutment forming part of the underreamer. The net result of transmitting the drilling weight directly through the supporting members, positively preventing their inward movement from expanded position, and positively preventing their outward movement beyond the maximum expanded position desired, effectively locks them and their associated roller cutters in expanded position, resulting in an extremely sturdy and rigid underreamer capable of enlarging the diameter of a well bore drilled through comparatively hard formations. The underreamer is so constituted that the drilling weight maintains its cutters in expanded position, which force is supplemented by

the hydraulic force of the drilling fluid passing through the tool.

Following completion of the underreaming operation, it is only necessary to discontinue the hydraulic expanding force and elevate the drilling string to cause the supporting members and the roller cutters to move downwardly along the expander portions of the tool body from their outwardly locked position and inwardly into retracted position. The tool may then be withdrawn readily through the casing to the surface of the well bore.

The particular embodiment of the invention disclosed in the drawings consists of a generally cylindrical main supporting body 10, preferably in one piece, which has a threaded box 11 in its upper end for attachment to a string of drill pipe (not shown), in the usual manner. This body is provided with a plurality of circumferentially spaced, longitudinal grooves 12 intermediate its ends merging into a cylindrical bore 13 through the upper part of the body continuing downwardly from the threaded box. A tube or wash pipe 14 is positioned in this bore with its lower end clamped against a shoulder 15 in the body by a collar 16 engaging its upper end and threaded into the body adjacent the box 11. The wash pipe is of much smaller diameter than the body bore 13 to form a longitudinal annulus 17 therearound. Leakage of fluid between the interior and exterior of the wash pipe 14 is prevented by a thread seal 18 in the collar engaging the wall 19 of the body bore, and by a rod seal 20 in the body adjacent the shoulder 15 engaging the wash pipe.

The base of each groove 12 is of irregular shape. Its upper portion merging into the body bore 13 is supplied by the wash pipe 14; its intermediate portion consists of an expander in the nature of a projection 21 in the body bounded by a shoulder 22 transversely of the body, a stop 23 or abutment extending downwardly of the body from this shoulder, and a cam 24 inclined downwardly and inwardly from the shoulder; and its lower portion is formed in the body and extends downwardly from the cam 24. The lower section of each groove is enlarged by recesses 25 on its opposite sides of sufficient size to accommodate a roller reaming cutter 26 when it is in retracted position as described hereinbelow.

A supporting member 27 for each roller cutter 26 is positioned in each groove 12, and has straight parallel sides 28 slidably engageable with the companion sides 29 of each groove. These members 27 are each provided with inner and outer depending legs 30, 31 defining an opening for receiving the roller cutter 26, which is preferably of the cone type. The cutter is carried between the legs 30, 31 on a bearing supporting pin 32 suitably attached thereto, as by welding material 33. Mounted on this pin are spaced apart inner and outer bearing plates 34, 35 having races 36 formed in their opposed, inner faces rollably engaging bearing balls 37 operable on companion races 38 formed in the roller cutter. This bearing arrangement transmits radial loads between the bearing supporting pin 32 and the cutter 26 as well as axial loads between the legs 30, 31 and cutter 26. It is to be understood, however, that any suitable type of bearing may be employed. It is to be noted that the provision of the inner and outer legs 30, 31 affords much greater support to the bearing pins 32 and also to the roller cutters 26 than a single leg would provide.

The bearing pins 32 are inclined in a downward and inward direction so that the back cone faces

39 of the teeth 40 on the cutters can begin cutting away the wall of the formation immediately upon outward expansion of the roller cutters.

The supporting member 27 projects inwardly intermediate its ends to provide upper and lower shoulders 41, 42. The inner surface 43 of its lower portion is inclined upwardly and outwardly to form a recess 44 with the lower shoulder 42 in which the projection 21 may be positioned when the supporting member 27 is in retracted position, with the lower shoulder 42 resting on the projection shoulder 22. Each supporting member is also furnished with bifurcated arms 45 extending upwardly from the shoulders 41, 42, which terminate in outwardly projecting fingers 46 receivable within an annular enlargement 47 of the body bore for engagement with an inwardly extending body flange 48 forming the upper end of the groove 12. The inner surfaces 49 of these arms are bevelled outwardly in an upward longitudinal direction and are also curved to conform generally to the radius of the wash pipe 14, so as to engage this pipe along substantially the entire bevel surfaces and limit the extent of outward movement of the supporting member 27 and its associated roller cutter 26.

The roller cutters 26 are movable outwardly hydraulically. A link 50 extends between the bifurcated arms 45 of each supporting member with its lower end connected to its shoulder portion 41, 42 by a pivot pin 51. The upper end of each link is mounted on an upper pin 52 extending between the depending ears 53 of the link end 54 of a cylinder 55 adapted to move within the annulus 43 formed between the wash pipe or tube 14 and the wall 19 of the body bore. The cylinder 55 includes a sleeve 56 extending upwardly from its link end 54, on the upper end of which an annular cylinder head 57 is threaded or otherwise suitably connected. This head 57 and link end 54 are slideable along the wash pipe, and these members 57, 54 and the sleeve 56 are slideable on the bore wall 19.

Disposed intermediate the link and head ends 54, 57 of the cylinder is an annular piston 58 suitably fastened to the wash pipe 14. As illustrated in the drawings, the attaching elements may consist of a lock ring 59 received within a groove 60 in the wash pipe and engaging an inner shoulder 61 on the piston 58 to prevent its downward movement on the wash pipe. Its upward movement is prevented by a retainer ring 62 engaging the lock ring 59 and secured to the piston by screws 63.

The cylinder head 57 and piston 58 are separated from one another to form a cylinder space 64 into which fluid may pass from the interior of the wash pipe 14 through its lateral ports 65. Leakage of fluid from this cylinder space 64 in an upward direction is prevented by a rod packing 67 slidably engageable with the exterior of the wash pipe 14, and by a piston ring 68 in a piston groove 69 adapted to slidably seal against the inner wall of the cylinder sleeve 56. To maintain the wall 19 of the body bore clean, additional seals 70 may be provided on the head 57 and link end 54 of the cylinder 55 for slidably engagement with such wall as the cylinder moves within the annulus 17.

Fluid pumped down the drilling string (not shown) passes into the wash pipe 14 and through the lateral ports 65 into the cylinder space 64 to force the cylinder head 57 and its connected sleeve 56 and link end 54 in an upward direction.

This action also moves the links 50 and supporting members 27 upwardly to cause outward expansion of the supporting members and roller cutters 26. As the cylinder head 57 moves upwardly within the bore 13 of the main body, the fluid in the annulus 17 thereabove can pass outwardly through the bleeder holes 71 in the body at its upper end. Any fluid within the cylinder sleeve 56 between the piston 58 and link end 54 can escape between the latter and the wash pipe 14, since there is no seal therebetween.

The pressure necessary to move the cylinder 55 in an upward direction so as to produce outward expansion of the roller cutters may be obtained in a number of ways. In the present instance, the flow of fluid from the bottom end of the wash pipe 14 is restricted so as to build up a back pressure thereon of sufficient value to elevate the cylinder 55 and hold it in such elevated position so long as a sufficient quantity of drilling mud is being pumped through the tool. The fluid exits from the wash pipe 14 through nozzles 72 adapted to direct cleaning fluid on the cutters 26, and through a comparatively small central passage 13 in the lower end of the body, which delivers fluid to lower nozzles 74 capable of directing it onto pilot blades 15 at the lower end of the body 10. The openings through all of these nozzles 72, 74 are of a lesser combined area than the internal area of the wash pipe 14, in effect producing a combined restriction to the passage of fluid in the nature of an orifice capable of building up a back pressure in the fluid within the wash pipe 14 and cylinder space 64 more than sufficient to elevate the cylinder 55.

The tool is run through the casing A on the end of a string of drill pipe with the parts in retracted position, as shown in Figure 1. The supporting members 27 are in their innermost position, with the roller cutters 26 contained within the side pockets 25 and grooves 12. When in such position the inner shoulders 42 engage the projections 21, and the cylinder 55 is in its lowermost position with its head 57 adjacent the piston 58. Upon reaching the desired location below the casing shoe B, rotation of the tool is started and drilling mud is pumped down the drilling string. Due to the flow restrictions offered by the various nozzles 72, 74, the pressure of the fluid in the wash pipe and cylinder space is increased to urge the cylinder 55 in an upward direction hydraulically. Such upward movement pulls the links 50 and supporting members 27 in the same direction. As the inclined face 43 on each supporting member rides upon the upwardly diverging expander surface or cam 24, the supporting member 27 and the roller cutter 26 begin enlarging the well bore. As the bore diameter increases, the cylinder 55 continues to move upwardly, to shift the supporting members upwardly to a corresponding extent along their cam surfaces 24 and the rollers 26 radially outwardly. The effective hole enlarging diameter of the roller cutters is thus increased until the maximum lateral outward diameter is reached, in which the straight faces or surfaces 16 on the supporting members engage the straight longitudinal stops or abutments 23 on the body projections 21. The limit of this upward movement is positively determined by engagement of the upper shoulder 41 on the supporting member with the body portion or flange 48 defining the upper end of the longitudinal groove 12. When in this position, it is preferred that the longitudinal bevelled surfaces 49 of the arms contact the wash pipe 14 so

as to limit the maximum outward movement of the roller cutters 26.

With the cutters in this outward position, it is apparent that they have enlarged the well bore to form a shoulder on which the teeth of the roller cutters can operate as the underreamer is rotated. Once this shoulder is formed, the required drilling weight is imposed on the cutters and the tool gradually lowered as the formation shoulder is drilled away. The cuttings are removed by the drilling mud or other fluid issuing from the reamer nozzles 72, which are so arranged as to direct the fluid onto the cutters 26 when they are in expanded position, to keep them free of formation material and effective for maximum penetration into the formation shoulder.

With the tool performing its underreaming operation as a result of its outward expansion, it is to be noted that the drilling weight on the cutters 26 is imposed directly upon them through the supporting members 27, because of the engagement of the upper shoulders 41 with the main body of the tool. Moreover, the drilling torque is transmitted directly from the body 10 to the supporting members 27 by engagement of the groove sides 29 with the sides 28 of these members. It is further to be noted that the force of the formation tending to move the cutters 26 and supporting members 27 inwardly to a smaller effective diameter is resisted through engagement of the longitudinal surfaces 16 of the supporting members with the longitudinal surfaces or abutments 23 on the body projections 21. These two surfaces 16, 23 are substantially parallel to the tool axis, so that there is no component of force effective to move the supporting members 27 downwardly along their expanders 24 and back to retracted position. Once the cutters have been expanded, they will be retained in that position by the drilling weight and the cooperation between the surfaces 16, 23. This maintenance of the cutters 26 in outward position is assisted by the hydraulic fluid force tending to keep the cylinder 55, and also the cutters, in elevated position.

After the hole has been underreamed or enlarged to the required length, the pumping action is discontinued and the drilling string and underreamer elevated in the well bore. Frictional resistance of the cutters 26 against the wall of the hole tends to prevent their upward movement, resulting in the elevation of the main body 10 and wash pipe 14 without a corresponding elevation of the supporting members 27 and their associated links 50 and cylinder 55. The abutment surface 23 of the body projections 21 are therefore pulled upwardly within the recess 44 in the supporting members, allowing the latter to move relatively in a downward direction along the inclined expander surfaces 24 and inwardly to a retracted position within the body 10. The extent of this relative downward and inward movement of the supporting members and roller cutters is limited by engagement of the inner shoulders 42 with the projection shoulders 22 and by engagement of the fingers 46 with the internal flange 48 defining the upper ends of the grooves 12. Of course, as the supporting members 27 are moved downwardly relative to the body, the cylinder 55 is also moved downwardly with respect to the piston 58 to its initial position.

In the event that the frictional resistance offered by the wall of the well bore is insufficient to effect retraction of the supporting members 27 and rollers 26 into the confines of the under-

reamer body, a step 77 provided on the exterior of each supporting member near its shoulder 41 will engage the bottom end of the well casing step B and positively prevent elevation of the supporting members 21 for the time being, thus allowing the tool body 10 to be elevated with respect to the supporting members 21 and the projections 21 moved upwardly into their recesses 44, so as to permit inward swinging of the supporting members and cutters into retracted position within the lower ends of the grooves 48 and the adjacent recesses 28.

When in retracted position, the supporting members and cutters are movable upwardly through the well casing with material clearance.

The pilot portion 78 of the tool may be omitted, but it is preferred to include it, since it centers the tool, and its cutter can operate upon any bridges that might have formed in the well bore.

In assembling the tool, the piston 58 is secured to the wash pipe 4. The links 56 are pivotally mounted on the cylinder 55, and this combination, without its cylinder head 57, is placed over the wash pipe from the bottom end thereof. The cylinder head 57 is then placed over the other end of the wash pipe and is threaded into the cylinder sleeve 54 so that the head 57 and link end 56 are on opposite sides of the piston 58. This sub-assembly is then inserted into the body 10 through its upper box end, and the collar 10 threaded into the body until the wash pipe engages the shoulder 19 in the body. Each supporting member 21 with a roller cutter 24 already mounted thereon is then mounted in place by inserting its bifurcated arms 48 into the groove 47 straddling the link 56. The supporting member 21 is placed in its retracted position, and the pivot pin 51 inserted through a transverse hole 79 in the body adjacent the projections 21 and into and through the supporting arms 48 and lower end of the link. Removal of this pin 51 is prevented by thereafter threading a plug 79 into the body hole. Disassembly of the device is accomplished through a reversal of the aforementioned steps.

It is therefore apparent that an hydraulically expandable roller underreamer has been provided that positively holds roller cutters in their maximum outwardly expanded position, in which the drilling weight is imposed directly onto the cutters, in which the extent of outward movement of these cutters is positively limited, and in which the drilling torque is transmitted directly from the tool body to the supporting members for the roller cutters. The tool members are expanded simply through hydraulic action, and the tool members are moved back to retracted position by merely stopping the pump and taking an upward strain on the drilling string and underreamer body.

I claim:

1. A rotary underreamer for operation in a well bore, including a body adapted for connection to a tubular drilling string, a supporting member movable axially along said body, said supporting member having an upwardly extending arm, a cutter on the lower end of said supporting member, a projection on said body engageable with said supporting member between said cutter and arm, means connected to said supporting member for moving it upwardly along an expander surface on said projection to cause said projection to force said cutter laterally outwardly of said body, a first coating means on said projection above said expander surface having a surface substantially

parallel to said body axis and engageable with said supporting member for holding said cutter in such outward position, a second means on said body engageable with said arm for limiting the extent of lateral outward movement of said cutter, a third means on said body engageable with said supporting member at the base of said arm to limit the extent of upward movement of said supporting member on said body, said first, second and third means being engageable simultaneously with said supporting member and its arm to hold said cutter in its outward position and prevent its inadvertent inward movement.

2. A rotary underreamer for operation in a well bore, including a body adapted for connection to a tubular drilling string, a supporting member movable axially along said body, said supporting member having upwardly extending bifurcated arms, a cutter on the lower end of said supporting member, a projection on said body engageable with said supporting member between said cutter and arms, means connected to said supporting member for moving it upwardly along an expander surface on said projection to cause said projection to force said cutter laterally outwardly of said body, said means comprising a link pivotally connected to said supporting member and positioned between said bifurcated arms, a first coating means on said projection above said expander surface having a surface substantially parallel to said body axis engageable with said supporting member for holding said cutter in such outward position, a second means on said body engageable with said arms for limiting the extent of lateral outward movement of said cutter, a third means on said body engageable with said supporting member at the base of said arms to limit the extent of upward movement of said supporting member on said body, said first, second and third means being engageable simultaneously with said supporting member and its arms to hold the cutter in its outward position and prevent its inadvertent inward movement.

3. A rotary underreamer for operation in a well bore as defined in claim 2, wherein said arms have outwardly projecting fingers on their upper ends positioned above and engageable with an inwardly extending flange on said body for limiting the extent of downward movement of said supporting member along said body.

4. A rotary underreamer for operation in a well bore; including a body adapted for connection to a tubular drilling string, a supporting member movable axially along said body and having an upwardly extending arm, a cutter on the lower end of said supporting member; an outwardly directed projection on said body having a lower expander surface inclined downwardly and inwardly, an upper transverse shoulder, and a stop surface between said shoulder and expander surface substantially parallel to the axis of the body; means connected to said supporting member for moving it upwardly along said expander surface to cause the latter to force said cutter laterally outwardly of said body; said stop surface being engageable with said supporting member for holding said cutter in such outward position; means on said body engageable with said arm for limiting the extent of lateral outward movement of said cutter; means on said body engageable with said supporting member at the base of said arm to limit the extent of upward movement of said supporting member on said body; said stop surface and both of said engageable means being engageable simultaneously with said

supporting member and its arm to hold said cutter in its outward position and prevent its inadvertent inward movement; said supporting member having a shoulder adapted to rest on said transverse shoulder when said cutter is in retracted position with respect to said body.
